UNITED STATES PATENT OFFICE.

JOHN RAILTON, OF CHEBOYGAN, MICHIGAN, ASSIGNOR TO IGNATZ MAYER, OF DETROIT, MICHIGAN.

TRUSS.

SPECIFICATION forming part of Letters Patent No. 731,709, dated June 23, 1903.

Application filed February 24, 1903. Serial No. 144,693. (No model.)

To all whom it may concern:

Be it known that I, JOHN RAILTON, a citizen of the United States, residing at Cheboygan, in the county of Cheboygan and State of Michigan, have invented certain new and useful Improvements in Trusses, of which the following is a specification, reference being had therein to the accompanying drawings.

The invention relates generally to trusses for the treatment of various forms of hernia; and it consists in the novel construction of the truss-pad, which is so formed as to admit of the application of pressure at the precise point or points in the manner hereinafter set forth.

The invention further consists in the peculiar arrangement and combination of the various parts of the pad, as will be presently described, and illustrated in the drawings, in which—

Figure 1 is a top plan view. Fig. 2 is a vertical central section through the pad, and Fig. 3 is a bottom view thereof.

In construction the pad is preferably of oval configuration, and consists, essentially, of an outer inclosing casing A and an inner pneumatic pad member B. The casing is preferably, but not necessarily, made of yielding material and has a circular opening a formed in its top and a central aperture b in its under face or side. Arranged within the casing is the pad member previously referred to, which may be made of any suitable material and is adapted when inflated to protrude in the manner indicated in Fig. 2 through the casing-aperture. As a matter of preference the inner member is in the form of a rubber bag provided with a suitable inflating-nozzle D, projecting through the opening a and covered in the usual manner by a cap E.

F and G represent circular plates at the top of the casing and arranged, respectively, within and upon the exterior thereof. These plates are centrally apertured, as at c, to allow the inflating-nozzle to pass therethrough and are so proportioned as to overlap the marginal portion d of the outer cover.

H is an oblong plate to which the usual band (not shown) that passes about the body of the wearer is attached. This is mounted upon the upper plate G, and the several plate-sections are connected by suitable devices, such as screws e, the marginal portion of the casing being tightly clamped between the plates, as illustrated.

While I have shown a single aperture in the casing, it will be obvious that a plurality of openings may be formed in the under part thereof, so that the bag will protrude at several places, permitting its application at a number of distinct points where pressure is required.

By constructing the pad in such manner that only a part or certain portions thereof are employed to exert pressure it can be properly and most accurately fitted to the wearer and is comfortable in use.

What I claim as my invention is—

1. A truss-pad, comprising an outer apertured casing, and an inner inflatable member contacting with the marginal portions of the casing about the aperture and having, upon inflation, a relatively small portion thereof protruding uninterruptedly through said aperture.

2. A truss-pad, comprising an outer inclosing casing of yielding material, having an aperture formed in its under side, and an inner pneumatic bag adapted when inflated to protrude through the casing-aperture.

3. A truss-pad, comprising an oblong inclosing casing formed of yielding material having an opening in its top and an aperture formed in its under face, a rubber bag within the casing adapted when inflated to protrude through the casing-aperture, and an inflating-nozzle for the bag projecting normally through the opening in the casing-top.

In testimony whereof I affix my signature in presence of two witnesses.

JOHN RAILTON.
